United States Patent Office

Des. 203,631
Patented Feb. 1, 1966

203,631

LITTER RECEPTACLE

Eleanor V. Kingsley, 502 W. Service Ave.,
Pomona, Calif.

Filed Apr. 5, 1965, Ser. No. 84,595

Term of patent 14 years

(Cl. D58—17)

FIGURE 1 is a perspective view of a litter receptacle, showing my new design;
FIGURE 2 is a top view thereof;
FIGURE 3 is a front elevational view thereof;
FIGURE 4 is a rear view thereof; and
FIGURE 5 is a bottom view thereof.

I claim:

The ornamental design for a litter receptacle, as shown.
